UNITED STATES PATENT OFFICE

169,837

SPREADER TOOL

Julius Blander, Brooklyn, N. Y.

Application July 18, 1952, Serial No. 20,682

Term of patent 14 years

(Cl. D54—13)

To all whom it may concern:

Be it known that I, Julius Blander, a citizen of the United States, residing at Brooklyn, in the county of Kings, in the State of New York, have invented a new, original, and ornamental Design for a Spreader Tool, of which the following is a specification, reference being had to the accompanying drawing, forming a part hereof.

Fig. 1 is a perspective view of a spreader tool showing my new design;

Fig. 2 is a top plan view;

Fig. 3 is a front elevational view;

Fig. 4 is an end elevational view; and

Fig. 5 is a rear elevational view thereof.

I claim:

The ornamental design for a spreader tool, as shown.

JULIUS BLANDER.
